UNITED STATES PATENT OFFICE.

GEORGE T. KENNEDY, OF CALGARY, ALBERTA, CANADA.

AIR-COMPRESSOR.

1,238,683.

Specification of Letters Patent. Patented Aug. 28, 1917.

Application filed February 7, 1916. Serial No. 78,736

To all whom it may concern:

Be it known that I, GEORGE T. KENNEDY, a subject of the King of Great Britain, residing at Calgary, in the Province of Alberta and Dominion of Canada, have invented new and useful Improvements in Air-Compressors, of which the following is a specification.

This invention relates to improvements 10 in air compressors and has particular application to a centrifugal compressor.

In carrying out the present invention, it is my purpose to provide a centrifugal air compressor which will embody in its 15 construction an inner stationary cylinder formed with valve controlled ports and an outer revolving cylinder surrounding the stationary cylinder and having slots formed therein and equipped with outwardly projecting tangentially curved blades adapted to draw the air through the slots and force the same through the valved ports of the stationary cylinder into the latter so that the compressed air may be taken from the 20 inner cylinder.

It is also my purpose to provide a centrifugal air compressor which will embody comparatively few parts and these so arranged and correlated as to reduce the possibility of derangement to a minimum and wherein the parts of the compressor may 25 be lubricated and cooled.

With the above and other objects in view, the invention consists in the construction, 30 combination and arrangement of parts hereinafter set forth in and falling within the scope of the claims.

In the accompanying drawings;

Figure 1 is a view in elevation of an air 40 compressor constructed in accordance with the present invention.

Fig. 2 is an end view of the same.

Fig. 3 is a longitudinal sectional view 45 therethrough.

Fig. 4 is a cross sectional view through the compressor.

Fig. 5 is a perspective view of the stationary cylinder showing the arrangement 50 of the passages for the cooling fluid and the valved ports.

Fig. 6 is a similar view of the revolving cylinder carrying the fan blades.

Referring now to the drawings in detail, 55 1 designates a stationary cylinder formed with longitudinally extending passages 2 spaced apart around the cylinder and adapted to

receive a cooling liquid. Formed in the outer surface of the cylinder 1 adjacent to the respective ends thereof are annular grooves or raceways 3, while formed in the cylinder between the grooves 3 are a plurality of ports 4 and arranged in each port 4 is an inwardly opening check valve 5 which permits air or other fluid to flow through the ports and into the cylinder, but prevents the return of such fluid through the ports. Surrounding the cylinder 1 and adapted to rotate thereabout is a cylinder 6 of less length than the cylinder 1 and formed in the inner wall of the cylinder 6 adjacent to the respective ends thereof and coinciding with the grooves or raceways 3 are grooves or raceways 7 and disposed within these alining raceways are ball bearings acting to reduce the friction between the revolving cylinder and the stationary cylinder in the rotation of the cylinder 6. Formed in the cylinder 6 between the ends thereof are longitudinal slots 8 spaced apart around the cylinder and communicating with the ports 4. The under surface of the cylinder 6 contiguous to corresponding side edge walls of the slots 8 is undercut as at 9. Secured to said side edge walls of the cylinder 6 and projecting outwardly therefrom are 85 blades 10 and each blade 10 is curved in cross section and disposed substantially at a tangent to the cylinder. Surrounding the outer revolving cylinder 6 adjacent to the respective ends thereof and fixed thereto are end plates 11 closing the ends of the spaces between the blades 10 and carried by the end plates 11, while surrounding the blades 10 and the revolving cylinder is a casing 12 composed of suitable material 90 formed in such manner that air may be drawn through such casing. The projecting ends of the inner stationary cylinder 1 are mounted in suitable alining bearings which act to support the compressor as shown in 100 Figs. 1 and 3, while fixed to one end of the cylinder 6 is a pulley 14 whereby the revolving cylinder and the blades carried thereby may be rotated. One end of the inner cylinder is open so that the compressor may be 105 connected with a suitable storage tank. Any suitable means may be employed for lubricating the compressor.

In practice, the cylinder 6 is rotated about the stationary cylinder and in the rotation of the cylinder 6 the blades 10 act to draw air toward the slots 8 and compress such air 110

to force the same through the valved ports 4 and into the stationary cylinder whence such air may be conveyed to a suitable receiver.

5 While I have herein shown and described the preferred form of my invention by way of illustration, I wish it to be understood that I do not limit or confine myself to the precise details of construction herein described and delineated, as modification and variation may be made within the scope of the claims and without departing from the spirit of the invention.

I claim:

- 15 1. In a centrifugal air compressor, a stationary cylinder, formed with valved ports, a revolving cylinder surrounding said stationary cylinder and formed with longitudinal slots spaced apart about said revolving cylinder, and blades secured to corresponding edge walls of said slots respectively and projecting outwardly from such revolving cylinder substantially at a tangent thereto and curved in cross section 25 whereby air may be drawn into said slots and compressed through said ports into said stationary cylinder in the movement of the revolving cylinder.
2. In a centrifugal air compressor, a stationary cylinder formed with valved ports, a revolving cylinder surrounding said stationary cylinder and formed with longitudinal slots spaced apart about said revolving cylinder, blades secured to corresponding 35 edge walls of said slots respectively and

projecting outwardly from such revolving cylinder substantially at a tangent thereto and curved in cross section whereby air may be drawn into said slots and compressed through said ports into said stationary cylinder in the movement of the revolving cylinder, plates closing the ends of said revolving cylinder, and a casing inclosing said cylinder and secured to said end plates and formed in such manner that air may be 45 drawn therethrough.

3. In a centrifugal air compressor, a stationary cylinder formed with valved ports, a revolving cylinder surrounding said stationary cylinder and formed with longitudinal slots spaced apart about said revolving cylinder, and blades secured to corresponding edge walls of said slots respectively and projecting outwardly from such revolving cylinder substantially at a tangent 55 thereto and curved in cross section whereby air may be drawn into said slots and compressed through said ports into said stationary cylinder in the movement of the revolving cylinder, said stationary cylinder being formed with longitudinally extending passages through which a cooling fluid may be passed.

In testimony whereof I affix my signature in presence of two witnesses.

GEORGE T. KENNEDY.
